ROLLING MILL

Joseph M. O'Malley, Worcester, Mass., assignor
to Morgan Construction Company, Worcester,
Mass., a corporation of Massachusetts

Application February 19, 1946, Serial No. 648,701

5 Claims. (Cl. 80—55)

1

This invention relates to rolling mills of the type having a pair of vertical rolls for rolling metal bars which travel in a substantially horizontal path between the rolls, and more particularly to a construction and arrangement of parts which will facilitate the removal and replacement of the rolls.

The handling of rolls in connection with a large rolling mill presents a difficult problem, and this is particularly true in mills having gearing located above the rolls and arranged to drive the rolls from their upper ends. The weight of each roll is so great that an overhead crane must be employed for roll-handling purposes, yet the gearing prevents removal of the rolls by direct upward movement unless the gearing itself is first removed. This of course is expensive and time-consuming. The roll neck bearings in a large mill are also very heavy, and they further complicate the problem of roll handling.

It is accordingly one object of the invention to provide a vertical rolling mill so constructed and arranged as to greatly facilitate the removal and replacement of the rolls.

It is a further object of the invention to provide a rolling mill having vertical rolls driven by gearing at their upper ends, the construction being such that the rolls may be removed and replaced in an expeditious manner without disturbing the driving gears.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is a section through a vertical rolling mill, the section being taken principally in the plane of the roll axes, the bearing chocks for the left-hand roll being sectioned in a laterally offset plane, with apparatus in position to remove the said roll;

Fig. 2 is a front elevation of the mill, showing one roll in the process of removal;

Fig. 3 is a section taken on the line 3—3 of Fig. 1;

Fig. 4 is a section taken on the line 4—4 of Fig. 1;

Fig. 5 is a perspective view of a roll handling apparatus;

Fig. 6 is a perspective view of a modified roll

2

handling apparatus, capable of handling both rolls simultaneously;

Fig. 7 is a front elevation of the mill, partially broken away, showing the apparatus of Fig. 6 in position to remove the rolls; and

Fig. 8 is a front elevation of the mill, showing both rolls in the process of removal.

The embodiment illustrated comprises a pair of separate roll housings 10 each of which supports upper and lower bearings or chocks 11 having vertically aligned bores for the reception of the necks of a vertical roll 12. The two rolls 12 are located in laterally adjacent positions. As best shown in Fig. 3, the housings provide a laterally open pocket 14 for each chock 11, the sides of the pocket and chock being correspondingly flared in an outward direction. The rolls are provided at their upper ends with fluted wabblers 15 of the usual shape. One or both of the housings are movable laterally to vary the distance between the rolls, and for this purpose both housings are slidably supported on a pair of horizontal rails 16 (Fig. 4). Any suitable power operated means may be employed to move the housings along the rails. To support the housings in opposition to the lateral forces resulting from the rolling pressure, four transverse horizontal tension bars 18 are provided. There are two of these bars at each side of the housings, one above the other, and they are firmly connected to the right-hand housing. The left ends of the bars are connected by yokes (not shown) which carry horizontal screws 19 (Fig. 1) in engagement with the left-hand housing.

Power transmitting mechanism is provided to drive the rolls 12. For this purpose a vertical shaft 21 (Fig. 1) is rotatably supported in each housing, in a position adjacent the outer side of the corresponding roll. A bevel gear 22 is mounted on the lower end of each shaft and meshes with a bevel pinion 23, each gear and pinion being enclosed in a casing 25 carried by the housing 10 thereabove. Both the pinions 23 are slidably keyed to a transverse horizontal drive shaft 26 which extends through both gear casings 25, this shaft being rotated by any suitable source of power.

The vertical shafts 21 are connected to the rolls to drive the same. As shown, a gear housing 28 is mounted on the top of each roll housing, and within each gear housing there is mounted a pair of intermeshing vertical gears 29 and 30. Each driving gear 29 is substantially aligned with the corresponding shaft 21, and each driven

gear 38 is substantially aligned with the corresponding roll 12. Since it is impossible, as a practical matter, to either obtain or maintain exact alignment between these gears and their corresponding rolls and shafts, these parts are connected in such a manner as to avoid any harmful effects from misalignment. As shown, each driving gear 29 is of hollow construction to provide a central longitudinal bore or passage 32 therethrough for the reception of a vertical spindle 33. The lower end of this spindle is formed with a head 34 multi-splined externally and fitting within an internally splined coupling member 36 secured to the upper end of the corresponding shaft 21. On the upper end of each spindle 33 there is secured a head 37 multi-splined externally and fitting within an internally splined coupling member 38 attached to the upwardly projecting hollow shaft of the gear 29. Each driven gear 30 is of hollow construction to provide a central longitudinal bore or passage 40 therethrough for the reception of a vertical spindle 41. The lower end of this spindle is formed with a head 42 which is multi-splined externally to provide a telescopic driving connection with a coupling member or sleeve 43 mounted on the wabbler 15 therebeneath. On the upper end of each spindle 41 there is secured a head 45 multi-splined externally and fitting within an internally splined coupling member 46 attached to the upwardly projecting shaft of the gear 30. The several splined or fluted joints are made with sufficient looseness to permit the spindles 33 and 41 to serve as universal spindles which will transmit power in a proper manner and without binding despite slight misalignment of the driving gears 29 with respect to the shafts 21 or of the driven gears 30 with respect to the rolls 12.

Referring now to Fig. 1, it will be seen that the left-hand spindle 21 has been raised to withdraw the head 42 from the coupling member 43 and the head 45 from the coupling member 46. By turning the spindle slightly about its axis to bring the head 45 out of matching relationship to the member 46, the spindle may be retained in its raised position, with the head 42 withdrawn into the lower portion of the bore 40. To facilitate such lifting of the spindles, eyes 47 are provided at their upper ends, so that a crane or hoist may be employed for the purpose. In this manner the gearing may be disconnected from the rolls, so that each roll 12 with its associated bearing chocks 11 and coupling member 43 may be removed as a unit assembly from the housing.

In order to facilitate the handling of each roll assembly there is provided a roll handling apparatus arranged to be suspended from an overhead crane or the like. In Fig. 5 there is shown one suitable form of roll handling apparatus 49 comprising two spaced uprights 50 from which four parallel bars or fingers 51 project horizontally. These fingers are arranged in two vertically spaced pairs. On the outer end of each finger there is formed an upwardly projecting lug 53. Two horizontal struts 54 are provided to hold the uprights 50 in the proper spaced relationship, these struts being located between the inner ends of the respective pairs of fingers. The uprights 50 extend for a considerable distance upwardly above the upper pair of fingers, and their upper ends are brought inwardly toward one another to engage the opposite sides of a bar 55 which extends horizontally in the same direction as the fingers 51. This bar 55 is provided with an open-

ing 56 therethrough which lies substantially in a common vertical plane with the finger lugs 53. The various parts of this apparatus 49 are fastened together by welding or other suitable means.

10 The roll neck bearing chocks 11 are constructed and arranged for engagement with the fingers 51 of the apparatus 49. For this purpose each chock is provided with two recesses or pockets 58 located on opposite sides of the roll axis and arranged to receive the fingers 51 (Figs. 1 and 3). These recesses open outwardly, toward the corresponding chock for the opposite roll, and the outer ends of the recesses are flared or bell-mouthed 15 to facilitate the entrance of the fingers. The upper walls of the recesses 58 are slightly undercut near their inner ends, as shown in Fig. 1, to receive the finger lugs 53. Preferably the two pairs of fingers 51 are spaced apart vertically a distance slightly exceeding the vertical spacing of the recesses 58.

20 The operation of the invention will now be apparent from the above disclosure. The roll housings 10 will be separated as illustrated in Fig. 1, and the left-hand spindle 41 will be raised to disconnect it from the coupling member 43 therebeneath. The apparatus 49 will then be suspended from the hook 60 of a suitable crane, lowered into the space between the roll housings, 25 and then moved horizontally toward the left-hand roll 12 to bring the fingers 51 into the recesses 58 of the bearing chocks 11. The apparatus will then be raised slightly until the upper chock rests upon the upper fingers 51 and the lower chock rests upon the lower fingers 51, the weight of the roll 12 and of the coupling member 43 being carried by the lower chock. The entire roll and bearing assembly may now be moved outwardly and upwardly as shown in Fig. 2, until 30 the lower chock is above the level of the upper bars 18, whereupon it may be moved laterally between the gear housings 28. A new roll and bearing assembly may be placed in the mill by a reversal of this procedure. The gearing which 35 drives the rolls need not be disturbed at all.

40 In Figs. 6 to 8 there is shown a modification of the invention, including an apparatus 62 arranged to handle both rolls simultaneously. This apparatus comprises two spaced uprights 63 which carry four parallel horizontal cross-bars 64, arranged in two vertically spaced pairs. These bars 64 are symmetrically disposed with respect to the uprights, and each bar provides two oppositely projecting fingers, with an upwardly 45 projecting lug 65 on the end of each finger. Two horizontal struts 67 are provided to hold the uprights 63 in the proper spaced relationship, these struts being located between the central portions of the respective pairs of bars 64. A vertical plate 50 68 extends between the upper portions of the uprights 63, this plate being shaped to provide a pair of oppositely disposed hooks 69. The various parts of the apparatus 62 are fastened together 55 by welding or other suitable means.

60 The operation of this embodiment of the invention will be readily apparent. The roll housings 10 will be separated and both spindles 41 will be raised to disconnect them from the coupling members 43. The apparatus 62 will be suspended from the crane hook 60 by means of wire 65 rope slings 71 which engage the hooks 69. With the apparatus 62 lowered into position between the roll housings, the housings will be moved toward one another, causing the fingers 64 to 70 enter the recesses 58 of the bearing chocks 11, as 75

shown in Fig. 7. The crane hook will be raised slightly until the weight of the rolls and chocks is supported by the fingers 64, whereupon the roll housings will again be separated and the loaded apparatus 62 raised still further and carried away by the crane, as indicated in Fig. 8.

It will be recognized that the invention greatly facilitates the handling of rolls in a mill of the vertical type, and this is accomplished in such a manner that the roll-driving gears need not be disturbed. Since the roll neck bearings remain in place on the roll necks, the bearing surfaces are not exposed to dirt or possible injury.

Having thus described my invention, what I claim as new and desire to secure by Letters Patent is:

1. A rolling mill comprising a housing, and separate upper and lower roll neck bearings mounted on the housing and removable therefrom in a horizontal outward direction, the bearings having vertically aligned bores adapted to receive the necks of a vertical roll, each of the bearings having two recesses therein extending inwardly from the outer face of the bearing at opposite sides of the corresponding bore and adapted to receive the projecting fingers of a roll handling apparatus.

2. A rolling mill as set forth in claim 1, in which the housing has two vertically spaced pockets therein opening horizontally outward, the roll neck bearings being mounted in the pockets.

3. A rolling mill as set forth in claim 2, in which the sides of each pocket and bearing are correspondingly flared in the outward direction.

4. A rolling mill as set forth in claim 1, in which the recesses in the bearings are bell-mouthed at their outer ends.

5. A rolling mill as set forth in claim 1, in which the upper walls of the recesses are undercut near their inner ends.

JOSEPH M. O'MALLEY.
